ATTORNEY

UNITED STATES PATENT OFFICE.

AXEL ALFRID FRIBERG, OF PAWHUSKA, OKLAHOMA; JOSEPH D. MITCHELL ADMINISTRATOR OF SAID AXEL ALFRID FRIBERG, DECEASED.

ARCH SUPPORT.

Application filed December 10, 1923. Serial No. 679,768.

This invention relates to an arch support, at 8, and then the edges of the piece 6 are the general object of the invention being to provide a device of this nature which is adapted to be placed in a boot or shoe and which is shaped to hold the foot in proper position in the shoe and to provide a brace for the arch of the foot. 45

Another object of the invention is to provide a pad on the arch supporting part of 10 the device.

This invention also consists in certain other features of construction and in the combination and arrangement of the several parts, to be hereinafter fully described, illustrated in the accompanying drawings and 15 specifically pointed out in the appended claim.

In describing my invention in detail, reference will be had to the accompanying 20 drawings wherein like characters denote like or corresponding parts throughout the several views, and in which:

Figure 1 is a plan view of the device.

Figure 2 is a bottom plan view.

Figure 3 is a sectional view taken on line 3—3 of Figure 1.

Figure 4 is a sectional view on line 4—4 of Figure 1.

Figure 5 is a view of the metal plate. 30 In these views, 1 indicates an insole which is shaped to fit the shoe and which has one side turned up to form an arch support 2. A metal plate 3 is suitably secured to the under side of the portion 2 and a piece 6 of 35 leather or the like covers the plate and is suitably fastened to the insole 1. This piece forms a pocket to receive the plate, and the plate, the supporting part 2 and the piece are all provided with perforations, as 40 shown at 7. Cotton, wool or other soft material is inserted in the pocket to form a cushion on each side of the plate, as shown

This support is formed so as to give the arch of the foot sufficient support to hold it up and at the same time absorb any jar that would otherwise effect the arch of the foot. 50

It is thought from the foregoing description that the advantages and novel features 55 of my invention will be readily apparent.

I desire it to be understood that I may make changes in the construction and in the combination and arrangement of the several parts, provided that such changes fall within the scope of the appended claim. 60

What I claim is:

In combination, an inner sole having an arch-shaped portion, a piece of leather arranged beneath and spaced from said arch-shaped portion and having its edges stitched to said inner sole, defining a pocket by the intervening space, a substantially diamond-shaped metallic plate arranged within the pocket and longitudinally curved to conform to the adjacent curvature of the inner sole, said plate having openings at the ends thereof and adapted to receive fastening elements for securing the plate to the inner sole, the body portion of said plate being 65 perforated and spaced from the adjacent portion of the inner sole, said portion of the inner sole being perforated, and relatively soft material arranged in the pocket above and below said plate and held in place by 70 the perforations in said plate and inner sole. 75

In testimony whereof I affix my signature.

AXEL ALFRID FRIBERG.
